UNITED STATES PATENT OFFICE

JEAN PAUL AND THÉOPHILE DUCOUSSO, OF PARIS, FRANCE.

SYSTEM OF ELECTRICALLY-CONTROLLED SIGNALS FOR RAILWAYS.

No. 901,122.

Specification of Letters Patent.

Patented Oct. 13, 1908.

Application filed April 13, 1907. Serial No. 368,127.

To all whom it may concern:

Be it known that we, JEAN PAUL and THÉOPHILE Ducousso, citizens of France, residing at Paris, France, have invented new and useful Improvements in Systems of Electrically-Controlled Signals for Railways, (for which we have obtained a patent in France, No. 365,206, bearing date April 13, 1906,) of which the following is a specification.

This invention relates to an improved system of signals for railways, the said system being controlled electrically.

The invention consists of the features of construction and the combination and arrangement of parts hereinafter described and particularly pointed out in the claims.

The invention is illustrated in the accompanying drawings, in which:

20 Figure 1 is a front elevation Fig. 2 a side elevation, and Fig. 3 a plan view.

The invention includes a transparent casing 1, made of any suitable material, such as glass reinforced with wire, and provided 25 with a metallic brace 2. In said casing is located the movable signal which is composed of the two semi-circular portions 5 and 6.

4 indicates the support for the casing.

30 One part of the signal is provided with a colored glass 7, behind which is placed the light for use at night. Each part 5, 6 consists of a semi-circular support, 8, 9, fixed on a shaft 10, 11, and on which is fixed a sheet 35 of suitable material. The ends of the shafts 10, 11 are disposed on pivot 12, 13, fixed to the casing 1 or to the brace 2 of the same, and are inclined slightly to the vertical, as shown in Figs. 1 and 2, whereby said parts

40 will, by the action of gravity, assume the position shown in Fig. 1, that is, they will lie against the bottom 3 of the casing, and the signal will be set. When the way is clear and the signal is to be set so as not to be seen

45 by the engineer, the parts 5 and 6 are turned in the direction of the arrows *f* in Fig. 3 until they assume the position shown in Fig. 2. The effort necessary for producing said motion is furnished by an electro-magnet 14,

50 whose armature is connected through a suitable transmission 15, to a disk 16, fixed eccentrically on each one of the shafts. The

displacement of the armature by the action of the electrical current, gives thus a traction effort on said eccentric disks 16, and, thereby, produces the rotation of the shafts 10 and 11, and the turning up of the signal. As soon as the current is interrupted, the weight of the parts of the signal produces automatically the displaying of the same on the bottom of the casing. By this arrangement a signal having a great surface may be controlled electrically, by means of the weak current furnished by a primary pile.

It is further evident that the system of signal forming the object of the present invention is applicable to the various forms of signals used in railways, the forms of the signal and of the casing being varied according to each application.

Having thus described and ascertained the nature of our invention, we declare that what we claim is:

1. An improved system of signal electrically controlled for railways, comprising a transparent casing fixed on a suitable support, a movable signal in the said casing, the said signal consisting of two similar parts, two shafts by which said parts are pivotally mounted, disks eccentrically mounted on said shafts, an electro-magnet, an armature, connection from the armature to the disks, and means whereby the signal will be set automatically by the action of gravity.

2. An improved system of signal electrically controlled for railways, comprising a transparent casing fixed on a suitable support, a movable signal in the said casing, the said signal consisting of two similar parts, shafts by which said parts are pivotally mounted, each one of said shafts being slightly inclined in the vertical direction, a disk eccentrically mounted on each shaft, an electric magnet, an armature, connections from the armature to the disks for bringing the two parts of the signal together when the magnet is energized, said parts being returned to set position by the action of gravity.

3. An improved system of signals electrically controlled for railways, comprising a transparent casing fixed on a suitable support, a movable signal in the said casing,

the said signal consisting of two similar parts, shafts by which said parts are pivotally mounted, one of said parts being provided with a colored glass, and each one of said shafts having an eccentric point, an electro-magnet, an armature, connections from the armature to said points, the weight of said parts themselves insuring the automatic displaying of said part when the energizing of the electro-magnet is interrupted.

10 In testimony whereof we have signed our

names to this specification in the presence of subscribing witnesses.

JEAN PAUL.
THÉOPHILE DUCOUSSO.
